(57) **CLAIM**

We claim the ornamental design for a toy vehicle track ramp end, as shown and described.

DESCRIPTION

FIG. 1 is a top perspective view of the toy vehicle track ramp end;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken or dashed lines shown are included for the purpose of illustrating the unclaimed portions of the article and form no part of the claimed design. The shading illustrated in the figures is provided merely to represent the contour of the design and is not intended to be illustrative of the texture, gloss, or surface decoration.
